United States Patent Office

Des. 189,229
Patented Nov. 8, 1960

189,229

COMPRESSION TYPE PIPE JOINT

Martin S. Bowne, Clearfield, Ky., assignor to Lee Clay Products Company, Clearfield, Ky., a corporation of Kentucky

Filed Sept. 24, 1958, Ser. No. 52,740

Term of patent 14 years

(Cl. D91—3)

Fig. 1

Fig. 2

*Fig. 3**Fig. 4**Fig. 5*

Fig. 1 is an end elevational view showing my new design;

Fig. 2 is a side elevational view thereof;

Fig. 3 is a top plan view showing the outer ring members spread slightly apart;

Fig. 4 is a top plan view thereof; and

Fig. 5 is a bottom plan view thereof.

I claim:

The ornamental design for a compression type pipe joint, substantially as shown.
